INFANT'S BATHING APPLIANCE

Charles T. De Puy, Brighton, N. Y., assignor to
Trimble Nurseryland Furniture, Inc., Roch-
ester, N. Y., a corporation of New York

Application November 13, 1943, Serial No. 510,145

6 Claims. (Cl. 4—177)

This invention relates to an infant's bathing appliance, with more particular reference to the type of construction including a tub of flexible material provided with a hammock-like body rest for holding a baby above the bottom of the tub, and it has for its purpose to afford a practical, inexpensive, and efficient means for supporting the hammock-like body rest in proper position within the tub.

Efforts have heretofore been made to provide such a body rest with opposite disposed parallel rods that are positionable in flexible loops mounted at the ends of the tub, but such structure has the serious objection of a tendency for the rods to become disengaged from the loops unless of considerably greater length than the distance between the loops at opposite ends of a rod, and such structure also has no facilities for positioning the body rest at different elevations in relation to the bottom of the tub, and it is a purpose of this invention to provide flexible supporting means for the rods that carry the body rest and to construct such flexible supporting means so that rods of minimum length can be employed without likelihood of their becoming accidentally disengaged from the supporting means, while also permitting the rods to be raised or lowered at the foot end of the tub to maintain the foot end of the body rest in any one of the possible positions of adjustment.

Another purpose of the invention is to afford adjustable rod supporting means that can be readily and economically produced from a double thickness of fabric, affording the necessary adjustment without the use of metal fasteners or other metal parts and reducing to a minimum the amount of stock required for the wood or other rods of the body rest while holding the rods in such manner that the body rest is more firmly supported in the tub and held against excessive endwise movement.

To these and other ends, the invention consists in the construction and arrangement of parts that will appear more clearly from the following description when read in conjunction with the accompanying drawing, the novel features being pointed out in the claims at the end of the specification.

In the drawing:

Fig. 1 is a plan view of a folding bath stand and tub showing the application thereto of a preferred embodiment of the invention;

Fig. 2 is a longitudinal sectional view taken centrally of the tub;

Fig. 3 is a transverse sectional view on the line 3—3 of Fig. 2, and

Fig. 4 is a detail sectional view on the line 4—4 of Fig. 2.

5 The structure forming the subject matter of the invention is applicable to any infant's bath tub of collapsible form or otherwise, and is disclosed herein as applied to a conventional type of folding bath stand with a collapsible fabric

10 tub, and including pivotally connected folding cross-leg frames 1 and 2 including side rails 3 between which is suspended the collapsible tub 4.

Arranged within the tub 4 is a hammock-like fabric body rest 5 for supporting an infant some-
15 what above the bottom of the tub and including as a part thereof the head rest 6. The body rest 5 is provided with hems or tunnels at its side edges indicated at 7 and within which are located the rods 8 which may be of wood forma-
20 tion and extend beyond the ends of the body rest 5 to engage suitable devices for suspending the body rest within the tub.

At the head end of the tub, the rods 8 engage fabric loops 9 which are suitably fastened to the
25 side rails 3, the structure thus far described being of conventional form while the present invention has to do with the supporting means for the rods 8 at the foot end of the tub so as to prevent excessive endwise movement of the rods and hold them against accidental disengagement from their supporting devices, while permitting vertical adjustment of the body rest at the foot end of the tub to secure any desired inclination of the body rest, all of these results being ac-
30 complished by the structure that will now be de-
scribed.

On each side of the tub toward the foot end there is provided supporting means preferably including a strip 11 that is attached in any convenient fashion at its upper end to the side rail of the tub while its lower end extends downwardly into the tub and is positioned to receive the adjacent end of rod 8 at any selected elevation and hold it securely against displacement.

40 45 To accomplish this, the strip 11 is preferably composed of two thicknesses or plies of fabric stitched together along spaced parallel horizontal lines 12 to afford a series of vertically spaced receptacle portions for the adjacent end of the rod 8. The two thicknesses of fabric are also stitched along a vertical line 13 adjacent to its outer edge so as to form pockets which are closed on three sides and open on the side toward the end of rod 8.

50 55 With this arrangement, the end of the rod

abuts the closed end of the fabric pocket and is prevented thereby from moving endwise to an appreciable extent, thus obviating excessive sliding of the rod such as takes place if it is supported at both ends in loop portions, and so holding the body rest more firmly and obviating freedom of its endwise movement in the tub. This makes it considerably easier to hold and bathe an infant, and also permits employing shorter rods than would otherwise be required, thus contributing to a reduction in the cost of production. While each rod is thus firmly held against accidental removal as described, it can be easily adjusted by pushing it toward the head end of the tub and swinging the flexible pocket containing strip just described toward the foot end of the tub until the rod is disengaged, after which it can be reengaged with any of the pockets in the flexible supporting strip to sustain the body rest at any selected elevation at the foot end of the tub and thus vary the inclination of the body rest within the tub.

The structure described is inexpensive to produce and enables adjusting the height of the body rest at the foot end of the tub easily and expeditiously while at the same time permitting folding of the tub, eliminating the necessity of extra metal parts and maintaining the body rest and rods against excessive endwise movement.

While the invention has been described with reference to a specific embodiment, it is not confined to the exact details herein disclosed, and this application is intended to cover such modifications or departures as may come within the intent of the improvements and the scope of the following claims.

I claim:

1. In an infant's bathing appliance including opposite side rails with a tub mounted therebetween and a body rest of flexible material located above the bottom of the tub and provided with separate parallel rods at opposite edges, supporting means for said rods comprising loops of flexible material attached to the side rails at the head end of the tub and strips of flexible material attached at one end to the side rails at the foot end of the tub and each strip comprising two plies of fabric stitched along vertical and parallel horizontal lines forming a pocket to receive the adjacent end of one of said rods, said pocket being open on the side toward the rod and closed on the other three sides and acting to retain the rod and limit its endwise movement against accidental removal from the supporting means.

2. In an infant's bathing appliance including opposite side rails with a tub mounted therebetween and a body rest of flexible material located above the bottom of the tub and provided with separate parallel rods at opposite edges, supporting means for said rods comprising loops of flexible material attached to the side rails at the head end of the tub and strips of flexible material attached at one end to the side rails at the foot end of the tub and each strip comprising two plies of fabric stitched along vertical and horizontal lines forming a series of vertically spaced receptacle portions to receive the adjacent end of one of said rods in the selected vertical position of one of said receptacle portions and acting to prevent accidental removal of the rod from its supporting means.

3. In an infant's bathing appliance including opposite side rails with a tub mounted therebe-

tween and a body rest of flexible material located above the bottom of the tub and provided with separate parallel rods at opposite edges, supporting means for said rods comprising loops of flexible material attached to the side rails at the head end of the tub and strips each of which includes two thicknesses of flexible material attached at one end to the side rails at the foot end of the tub and stitched together along vertical and spaced parallel horizontal lines, each of said strips affording a series of vertically spaced receptacle portions to receive the adjacent end of one of said rods in the selected vertical position of one of said receptacle portions and acting to prevent accidental removal of the rod from its supporting means.

4. In an infant's bathing appliance including opposite side rails with a tub mounted therebetween and a body rest of flexible material located above the bottom of the tub and provided with separate parallel rods at opposite edges, supporting means for said rods comprising loops of flexible material attached to the side rails at the head end of the tub and strips of flexible material attached at one end to the side rails at the foot end of the tub and each having a series of vertically spaced pockets to receive the adjacent end of one of said rods in the selected vertical position of one of said pockets, each pocket being open on the side toward the rod and closed on the other three sides and acting to retain the rod against accidental removal from its supporting means and limit its endwise movement.

5. In an infant's bathing appliance including opposite side rails with a tub mounted therebetween and a body rest of flexible material located above the bottom of the tub and provided with separate parallel rods at opposite edges, supporting means for said rods comprising loops of flexible material attached to the side rails at the head end of the tub and strips of flexible material attached at one end to the side rails at the foot end of the tub and each having a series of vertically spaced pockets stitched thereto to receive the adjacent end of one of said rods in the selected vertical position of one of said pockets, each pocket being open on the side toward the rod and closed on the other three sides and acting to retain the rod against accidental removal from its supporting means and limit its endwise movement.

6. In an infant's bathing appliance including opposite side rails with a tub mounted therebetween and a body rest of flexible material located above the bottom of the tub and provided with separate parallel rods at opposite edges, supporting means for said rods comprising loops of flexible material attached to the side rails at the head end of the tub and strips including two thicknesses of flexible material attached at one end to the side rails at the foot end of the tub and stitched together along one vertical edge and along spaced parallel lines horizontally, each of said strips affording a series of vertically spaced pockets to receive the adjacent end of one of said rods in the selected vertical position of one of said pockets, each pocket being open on the side toward the rod and closed on the other three sides and acting to receive the rod and limit its longitudinal movement to prevent accidental removal of the rod from its supporting means.

CHARLES T. DE PUY.
